CLAIM

The ornamental design for a pruning tool, as shown and described.

DESCRIPTION

FIG. 1 is a perspective view of a pruning tool;

FIG. 2 is a right side view of a pruning tool;

FIG. 3 is a left side view of a pruning tool;

FIG. 4 is a top view of a pruning tool;

FIG. 5 is a bottom view of a pruning tool;

FIG. 6 is a front view of a pruning tool; and,

FIG. 7 is rear view of a pruning tool.

The broken lines in the drawings, shown in FIG. 3, illustrate portions of the pruning tool and form no part of the claimed design.
